CHALK HOLDER

Max Soifer, Los Angeles, Calif., assignor to The
Chalk Line, Inc., Los Angeles, Calif., a corpora-
tion of California

Application January 5, 1950, Serial No. 136,859

5 Claims. (Cl. 120—13)

1

This invention relates to new and useful improvements in scribes and the primary object of the present invention is to provide a device for use by tailors in marking garments.

Another important object of the present invention is to provide a chalk holder including a case, a chalk holding member slidably mounted in the case and embodying novel and improved means for retaining the holding member in a longitudinally adjusted position relative to the case.

Another object of the present invention is to provide a piece of chalk radically different in construction from chalk heretofore manufactured and whose conception when used in conjunction with the present holder being entirely new.

Yet another object of the present invention is to provide a chalk holder including a case and a chalk holding member that is quickly and readily moved up and down in the case to expose a chalk held by the member from the case whereby the chalk may be used for marking.

Another object of the present invention is to provide a chalk holder so constructed as to permit a chalk to be applied thereto or removed therefrom in a minimum time.

Another object of the present invention is to provide a chalk holder and chalk, the chalk being of uniform thickness throughout and sufficiently thin to make fine lines on cloth and to eliminate the necessity of sharpening the chalk.

Another object of the present invention is to provide a chalk holder and dispenser so designed as to eliminate a vexing problem of constant sharpening of chalk and will thus save considerable time on the part of the user. It will prove more economical over the old type of chalk since practically all of the chalk is used up.

A further object of the present invention is to provide a chalk holder wherein the user's fingers will not contact a chalk so that the chalk will remain substantially hard for continued use with minimum waste.

A still further aim of the present invention is the provision of a chalk holder and chalk therefor that are simple and practical in construction, strong and reliable in use, small and compact in structure, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the present invention;

Figure 2 is a longitudinal sectional view taken

2

substantially on the plane of section line 2—2 of Figure 1;

Figure 3 is an enlarged transverse vertical sectional view taken substantially on the plane of section line 3—3 of Figure 2;

Figure 4 is a fragmentary perspective view showing the manner in which the chalk holding member is adjusted within the case;

Figure 5 is a view showing the manner in which a new piece of chalk is placed in the holding member to replace a used piece of chalk;

Figure 6 is a fragmentary perspective view of the bottom of Figure 1;

Figure 7 is a view similar to Figure 2 but showing the chalk holding member moved relatively close to the discharge opening in the casing; and,

Figure 8 is a perspective view of the chalk per se.

Referring now to the drawings in detail, where-in for the purpose of illustration, there is disclosed a preferred embodiment of the present invention, the numeral 10 represents an elongated casing having spaced side walls 12 and 14, an end wall 16 and a discharge opening 18 at one end for chalk.

A chalk-holding member 20 is received in the casing 10 for movement longitudinally of the casing and toward or away from the discharge opening 18. The chalk-holding member 20 is formed from a single blank of bendable material, such as tin, and includes a split sleeve 22, a plate 24 projecting from one edge of the sleeve 22, and a retainer channel 26 projecting from the other edge of the sleeve and overlying the plate 24.

Means is provided for retaining the chalk-holding member 20 at a predetermined distance from the discharge opening 18. This means consists of a pair of substantially L-shaped locking members having first and second leg portions 28 and 30. The leg portions 28 are slidably received in the ends of the sleeve 22 whereas the leg portions 30 are slidably received in longitudinal slots 32 in the wall 12.

The outer longitudinal edges of the slots 32 are provided with longitudinally spaced teeth 34 for receiving lugs or dogs 36 on the leg portions 30. A spring member 38 received in the sleeve 22 yieldingly bears against the leg portions 28 to urge the leg portions 28 from the sleeve 22 and the lugs 36 toward the teeth 34 since the chalk-holding member 20 is disposed transversely of the casing 10 and the slots 32.

Finger gripping pieces 40 are integrally formed with the leg portions 30, overlie the wall 12 and project laterally from the casing so that the locking members can be simultaneously moved toward each other, by the thumb and middle finger of a user, to force the dogs 36 from the teeth and to permit the chalk-holding member 20 to be moved toward the discharge opening.

Upon release of the inward pressure on the pieces 40, the spring 38 will urge the dogs 36 toward the teeth 34.

Flanges or guide tongues 41 are provided at the ends of the sleeve 22 and are slidably received in longitudinal guide slots 42 formed in the wall 14 to prevent twisting of the chalk-holding member 20 relative to the casing or lateral movement of the chalk-holding member relative to the casing.

Guide plates 44 and 46 are integrally formed with the walls 12 and 14 respectively, at the open end of the casing 10. The plate 46 is flush with the wall 14 whereas the plate 44 slopes from the wall 12 and toward the wall 46 to form a restricted exit 48 or an exit smaller than the opening 18.

The numeral 50 represents an elongated piece of flat, thin chalk having a rib 52 at one end for reception in the channel 26 and between the channel 26 and plate 24.

In practical use of the present invention, the chalk-holding member 20 is moved outwardly of the opening 18 and between the plates 44 and 46 so that the rib 52 of the chalk can be placed into the retainer channel.

To remove a used piece of chalk C as shown in Figure 5, the rib 52 of a new piece of chalk is slipped into the retainer channel which will force the rib of the chalk C from the retainer channel to effect an ejection of the old chalk C.

While this invention purports to a chalk holder and improved chalk for the marking of cloth, it is in no way to be construed that this limits its usefulness as a marking device in other fields, nor is the shape of the rib 52 of the chalk or the shape of the channel 26 of the chalk holder as shown in the drawings to be construed as final in construction and can be altered in shape to conform to better manufacturing methods or as use dictates.

Having described the invention, what is claimed as new is:

1. A chalk holder comprising an elongated case having an open end, an upper wall and a lower wall, a hollow member received within the case and disposed transversely of the case, guide loops at the ends of said hollow member, the lower wall of said case having a pair of longitudinally extending slots slidably receiving said loops, means integrally formed with said hollow member for holding a piece of chalk, the upper wall of said case having a pair of longitudinal openings including toothed edges, a pair of locking members slidably carried by the hollow member and including upstanding end portions projecting through said openings, and means within said hollow member urging the upstanding portions of locking members toward the toothed edges of said longitudinal openings.

2. The combination of claim 1 wherein said locking members include finger gripping portions projecting laterally from the case and slidably supported upon the upper wall of said case.

3. A chalk holder comprising an elongated case having an opening at one end, a hollow member disposed transversely of the case and mounted within the case, said casing including a bottom wall having a pair of longitudinally extending spaced parallel slots, guides at the ends of said hollow member slidably received in said slots, said hollow member being open at its ends, a pair

of L-shaped locking members each including a longer leg and a shorter leg, the longer legs of said locking members being slidably received in the ends of said hollow member, said case including an upper wall having a pair of longitudinally extending parallel openings, said openings including outer toothed edges, the shorter legs of said locking members projecting through said pair of openings, dogs projecting laterally from the shorter legs of said locking member engaged between selected pairs of teeth on said toothed edges, a single spring member within said hollow member and biasing the longer legs of said locking members from the ends of the hollow member and the dogs against the toothed edges of said pair of openings, and means carried by said hollow member for supporting a chalk within the case.

4. A chalk holder comprising an elongated case having an opening at one end, a hollow member disposed transversely of the case and mounted within the case, said casing including a bottom wall having a pair of longitudinally extending spaced parallel slots, guides at the ends of said hollow member slidably received in said slots, said hollow member being open at its ends, a pair of L-shaped locking members each including a longer leg and a shorter leg, the longer legs of said locking members being slidably received in the ends of said hollow member, said case including an upper wall having a pair of longitudinally extending parallel openings, said openings including outer toothed edges, the shorter legs of said locking members projecting through said pair of openings, dogs projecting laterally from the shorter legs of said locking members engaged between selected pairs of teeth on said toothed edges, a single spring member within said hollow member and biasing the longer legs of said locking members from the ends of the hollow member and the dogs against the toothed edges of said pair of openings, a channel member carried by and paralleling said hollow member, and a plate carried by said hollow member and underlying said channel, said channel adapted to receive a rib on a chalk and said plate adapted to retain a rib on a chalk in said channel.

5. A chalk holder comprising an elongated case having a dispensing opening at one end, a hollow member slidably carried by and positioned in said case and disposed transversely of said case for sliding movement toward and away from the opening, said hollow member having open ends, a pair of locking members slidably mounted in the ends of said hollow member, means carried by said case engaging said locking members, and a single spring acting on both locking members and urging the locking members to their locked position.
